Primary Examiner — Barbara Fox

Assistant Examiner — Dana K Weiland

(57) **CLAIM**

The ornamental design for a display screen or portion thereof with a graphical user interface, as shown and described.

DESCRIPTION

FIG. 1 is a front view of a first embodiment of a display screen or portion thereof with a graphical user interface showing our new design; and,

FIG. 2 is a front view of a second embodiment of a display screen or portion thereof with a graphical user interface showing our new design.

The broken lines shown in the drawings represent portions of the display screen or portion thereof with a graphical user interface that form no part of the claimed design.
